United States Patent Office

Des. 177,928
Patented June 5, 1956

177,928

BUILDING

William Riseman, Wrentham, Mass., assignor to Richard's
Drive-In Restaurants, Inc., Boston, Mass., a corporation of Delaware

Application December 2, 1955, Serial No. 39,141

Term of patent 14 years

(Cl. D13—1)

Fig. 1

Fig. 2

Fig. 3

Fig. 1 is an elevational view of the building showing my new design;

Fig. 2 is an enlarged section on the line 2—2 of Fig. 3;

Fig. 3 is a top plan view of the building; and

Fig. 4 is a section, on a reduced scale, on the line 4—4 of Fig. 1.

I claim:

The ornamental design for a building, substantially as shown.
